UNITED STATES PATENT OFFICE.

CARL W. WEISS, OF NEW YORK, N. Y., ASSIGNOR OF ONE-HALF TO AUGUST MIETZ, OF NEW YORK, N. Y.

INCANDESCENT IGNITER FOR EXPLOSIVE-ENGINES.

SPECIFICATION forming part of Letters Patent No. 710,824, dated October 7, 1902.

Original application filed November 10, 1898, Serial No. 696,017. Divided and this application filed April 14, 1902. Serial No. 102,739. (No model.)

To all whom it may concern:

Be it known that I, CARL W. WEISS, a citizen of the United States, residing in the borough of Manhattan, city of New York, State 5 of New York, have invented certain new and useful Improvements in Incandescent Igniters for Explosive-Engines, of which the following is a specification, reference being had to the accompanying drawings, forming 10 a part hereof, this application being a division of application, Serial No. 696,017, filed November 10, 1898.

This invention is particularly concerned with the ignition of the explosive charge in 15 internal-combustion or explosive engines, and has for its object to provide an improved igniter which shall retain the heat sufficiently to ignite a charge at the beginning of every cycle of the engine, although the character 20 of the explosive mixture may vary and although the walls of the explosion-chamber are kept at a temperature sufficiently low to avoid premature ignition of the charge, even under high compression.

25 A further object is to provide an igniter which will not become filled with carbon and will itself give long service.

The invention will be more fully described hereinafter, with reference to the accompanying 30 drawings, in which, for purposes of illustration and explanation, it is shown as applied to an explosive-engine of a well-known type, and in which—

Figure 1 is a view, partly in elevation and 35 partly in longitudinal section, of an engine to which the invention is applied. Fig. 2 is a perspective view of the igniter-cartridge removed from the cylinder-head. Fig. 3 is a similar view of the bushing, by which the 40 igniter-cartridge is retained in its seat.

The cylinder A of the engine may be of ordinary construction and may be provided with a water-jacket A', as usual. The casing A² of the cylinder is preferably extended forward to inclose the cranks or crank-disks and to receive the bearings of the crank-shaft. The trunk-piston B may be connected, as usual, to the cranks or crank-pins of the crank-shaft C. The chamber inclosed by the 45 forward part of the casing A² constitutes a

convenient air-compression chamber, in which the air is compressed, as usual, at each forward movement of the piston. A port a admits the air from said chamber to the working cylinder or explosion-chamber when 55 the piston is at or near the forward limit of its stroke, such port being at other times covered by the piston. An exhaust-port a' is preferably provided in the wall of the cylinder to be covered by the piston, except as 60 the latter approaches the limit of its forward movement. A deflector b may be formed upon or secured to the face of the piston B for the purpose of directing the blast of air from the compression-chamber rearwardly 65 into the explosion-chamber.

The cylinder-head D is provided with a closed tubular extension D' to form the outer shell or seat for an independent shell or ignition-tube D², which is placed loosely—that 70 is, not permanently secured or tightly fitted—in its seat, and within which the ignition of the charge is effected. The inner shell or ignition-tube preferably has a relatively large bore for the greater portion of its length and 75 a contracted port d at its inner or forward end, this restricted orifice assisting in delaying the ignition of the charge until after the crank-pin has passed the dead-center and in retaining the relatively high temperature of 80 the ignition-tube. The use of an independent inner shell or ignition-tube, placed loosely within the outer shell and being by its separate formation to some extent insulated from the outer shell, prevents the outer shell 85 from quickly becoming porous through excessive heating and also, by prevention of radiation, enables the inner shell or ignition-tube to be more quickly raised to a temperature sufficient to ignite the charge and assists 90 in maintaining the temperature of the ignition-tube at the required degree. The inner shell or ignition-tube D² is retained in its seat by a bushing d', and therefore does not require any rigid fastening which would to 95 some extent impair the insulation which is attained by placing the ignition-tube loosely within its seat. Furthermore, the bushing, being in close contact with the cylinder-head, is cooler than the ignition-tube and does not 100

become heated to a degree sufficient to cause ignition of the charge, thereby avoiding the danger of premature ignition which would exist if the hot igniter-tube or ignition-tube 5 were itself presented to the explosive mixture in the working cylinder or explosive-chamber.

With the igniter constructed as above described the ignition of the charge within the 10 inner shell or ignition-tube D² is insured, while the walls of the working cylinder and of the compression-space are kept at a temperature which is insufficient to ignite the charge, although it is sufficient to vaporize the 15 oil. The effect of this is to permit the charge to be compressed without premature ignition more than is ordinarily the case, whereby the efficiency of the engine is increased.

Although the improved igniter may operate advantageously with various forms of devices for introducing and forming the explosive mixture within the explosion-chamber, nevertheless it is preferred to inject into the cylinder the oil which forms the basis of 25 the explosive mixture through a nozzle H, which is so located in the cylinder-wall as to discharge the oil upon or against a dash-plate d², which is preferably secured to the cylinder-head above the igniter—that is, between the 30 igniter and the nozzle—by any suitable means, such as a pump G, operated from the crank-shaft C of the engine in any suitable manner.

In the operation of the engine the oil is discharged upon the dash-plate and is immediately vaporized. At the same instant the blast of air from the port a carries the vapor throughout the working cylinder, forming therewith a uniform mixture. On the return 40 stroke of the piston the mixture is compressed, and as the piston reaches the limit of its rearward movement some of the mixture is forced into the ignition-tube D² and is thereby ignited. It will be observed that the 45 ignition-tube itself is protected from any blast of air that might cool it, and is therefore maintained at the proper temperature for ig-

nition, whereby the engine is enabled to run without load continuously. The igniter may be protected externally by a supplementary shell E, in which a lamp can be applied to the igniter in starting up the engine. It will be understood that the engine becomes self-igniting after it has once started in operation. 50

I claim as my invention—

1. In an explosive-engine, the combination with a tubular extension or shell extended rearwardly from the cylinder-head, of an independent, tubular igniting ignition-tube, open at its forward end only, placed loosely 60 within said shell or extension, substantially as described.

2. In an explosive-engine, the combination with a tubular extension or shell, extended rearwardly from the cylinder-head, of an independent, tubular igniting ignition-tube having a relatively large bore with a restricted port at its forward end, placed loosely within 65 said shell or extension, substantially as described.

3. In an explosive-engine, the combination with a tubular extension or shell, extended rearwardly from the cylinder-head, of an independent, tubular igniting ignition-tube, open at its forward end only, placed loosely 75 within said shell or extension, and a bushing secured in the forward end of the bore of said shell and independent of said ignition-tube, substantially as described.

4. In an explosive-engine, the combination 80 with a dash-plate secured to the cylinder-head, a tubular extension or shell extended rearwardly from the cylinder-head, and means to discharge oil upon said dash-plate, of an independent tubular igniting ignition-tube, 85 open at its forward end only, placed within said shell or extension, substantially as described.

This specification signed and witnessed this 10th day of April, A. D. 1902.

CARL W. WEISS.
